NOVELTY HAT

Frances Anthony Greenwald, Washington, D.C., assignor of one-third to Robert J. Patch, Chevy Chase, Md.

Filed May 20, 1959, Ser. No. 55,985

Term of patent 14 years

(Cl. D3—13)

FIG. 1.

The characteristic feature of my design resides in a novelty hat having an open-work top formed of double strands of yarn that are attached to the upper edge of the head band and which are drawn together in an elongated braid all as shown.

I claim:

The ornamental design for a novelty hat, as shown and described.
